(57) **CLAIM**

We claim the ornamental design for a swim board, as shown and described.

DESCRIPTION

FIG. 1 is a rear perspective view of a swim board;
FIG. 2 is a top plan view of the swim board of FIG. 1;
FIG. 3 is a bottom plan view of the swim board of FIG. 1;
FIG. 4 is a front elevational view of the swim board of FIG. 1;
FIG. 5 is a rear elevational view of the swim board of FIG. 1;
FIG. 6 is a left side elevational view of the swim board of FIG. 1; and,
FIG. 7 is a right side elevational view of the swim board of FIG. 1.
